UNITED STATES PATENT OFFICE

111,522

DESIGN FOR A WALL PLANT POT

Edwin H. Preston, Tampa, Fla.

Application July 14, 1938, Serial No. 78,487

Term of patent 14 years

To all whom it may concern:

Be it known that I, Edwin H. Preston, a citizen of the United States, residing at Tampa, in the county of Hillsborough and State of Florida, have invented a new, original, and ornamental Design for a Wall Plant Pot, of which the following is a specification, reference being had to the accompanying drawing, forming part thereof.

I claim:

The ornamental design for a wall plant pot, as shown.

EDWIN H. PRESTON.
